UNITED STATES PATENT OFFICE.

JOHN F. COATES, OF TERRE HAUTE, INDIANA.

OIL-BURNER.

SPECIFICATION forming part of Letters Patent No. 443,477, dated December 23, 1890.

Application filed August 11, 1890. Serial No. 361,646. (No model.)

To all whom it may concern:

Be it known that I, JOHN F. COATES, a citizen of the United States, and a resident of the city of Terre Haute, in the county of Vigo and State of Indiana, have invented certain new and useful Improvements in an Oil-Burner; and I do hereby declare that the following is a full, clear, and exact description of the invention, which will enable others skilled in the art to which it appertains to make and use the same, reference being had to the accompanying drawings, and to the letters of reference marked thereon, which form part of this specification.

15 My invention relates to that class of oil-burners wherein any volatile oil is converted to a vaporous state by means of steam, heated air, or other similar agent, said agent mixing with the oil and forming with it an inflammable vapor, and is used for heating purposes.

The objects of my invention are to attain a cheaper, more convenient, and more efficient heating agent by the use of petroleum and other combustible fluids. I attain these objects by means of the mechanism illustrated in the accompanying drawings, in which—

Figure 1 is a side elevation of the burner, with dotted lines showing the position of various internal parts. Fig. 2 is an end view showing the lower one-half of the burner, the feed-pipes, and the steam-dome, the steamways of the same being indicated by dotted lines. Fig. 3 is a view showing a cross-section of the burner, taken upon a horizontal plane through the center of the burner, the burner being upright, and showing the form and position of the steamways, the different pipes, &c. Fig. 4 is a view showing a cross-section of the steam-dome, the entrance to, and exit therefrom.

Similar letters refer to similar parts throughout the several views.

The letter A indicates the main body of the burner, which is a casting of iron, brass, or other suitable material, consisting of a cylinder a, a head b, said head extending beyond the sides of a and forming a flange b', and a heavy lug e, which extends about one-half way around the cylinder a. In the casting of A a tube-like passage is left through the center, winding around and opening into which are left a set of steamways or passages f and

f', as shown in Fig. 3. The steamways f and f' enter A at the head in the form of tubes, both below a horizontal plane and one on each side of a perpendicular plane through the center. After passing through the head b, and a short way into the lug e, the ways incline upward until on a level with the longitudinal axis of a. Then the two, being diametrically opposite, revolve in the same direction and in a spiral manner around about the passage through the center of a, opening into the same and extending toward the opposite end of a. At the forward end X of a 65 the two steamways f and f' open, diametrically opposite to each other, into a dome-like cavity c, said dome c converging toward X to within a short distance of the extreme end of a, where it begins to diverge and forms a bell-shaped mouth or orifice d.

The letter g indicates a hollow tube or pipe, which exactly fits into the passage through the center of a, and acts as an inner wall for the steamways f and f', and h is a smaller pipe, which passes through g, the same being held in position and apart from the inner walls of g by a threaded head i. As shown in Fig. 3, said pipe h protrudes through and beyond the head i, where it may be connected with an oil-supply pipe.

In Fig. 4, j indicates a hemispherical steam dome or chest, which is cast in one piece, of iron, brass, or other suitable material, and consists of the body l, the throat k, and the base m. The body l is a dome curving gradually up to and ending in the throat k, through which the steam-supply pipe n passes. The interior is a cavity, the walls of which are similar in form to the outside of the dome. The base m is of solid material, and extends over and beyond the bottom of the dome, forming a plate similar in form and size to the head b of the cylinder a. Through m there are drilled three holes, one in the center, through which the oil-supply pipe and head i pass, and the other two in such position as to coincide exactly and communicate with the respective entrances to the two steamways f and f' through b. The base m and the head b are fastened firmly together by means of large screws s.

To operate my burner I attach an oil-supply pipe to the pipe h and admit a small

flow of oil, which is ignited in the cavity *c*, the combustion of which produces a small amount of steam in the vessel which is to be heated. This steam is conducted through the supply-pipe *n*, and passes into the dome *J*, where it divides into two currents, each passing into one of the steamways *f* and *f'*, then passing around the pipe *g*, through the spiral ways, heating the same, and then passing on, escaping into the cavity *c*, where the two currents blow across one another, as shown in Fig. 3. The oil passing through tube *h* is heated evenly by the heat which is communicated from the pipe *g* and escapes into the cavity *c*, where it is cut by the two currents of steam and converted thereby into a vaporous state. This vapor uniting with the steam forms an inflammable vapor, which blows out through the orifice *d*, where it is ignited and produces an intense heat. The head *i* separates the two pipes *g* and *h*, leaving thereby an air-space between the two, the effect of which is to modify and even the temperature of the oil which passes through *h* and to prevent the same from boiling.

I am aware that prior to my invention contrivances were used by means of which steam and oil have been caused to combine in a vaporous state and produce thereby a heating agent. I do not therefore make any broad claim on such principle; but

What I do claim as my invention, and desire to secure by Letters Patent, is—

1. In an oil-burner, the combination of an

outer hollow cylinder *A*, consisting of the body *a*, provided with two internal spiral steamways *f* and *f'*, leading from the supply end to the discharge end, the dome-shaped condensing-chamber *c*, and the flaring orifice *d* at the discharge end, the head *b*, cast integral with the body *a*, a pipe *g*, fitted closely within *a*, an oil-pipe *h* within pipe *g*, and the steam-dome *J*, consisting of the body *l*, the throat *k*, a base *m*, similar to and fixed to the head *b* in such manner that the respective steamways perforating each shall coincide, all substantially as described and set forth.

2. The combination, in an oil-burner, of a cylinder *A*, consisting of a body *a*, having a dome-shaped condensing-chamber *c* and the flaring orifice at its discharge end *d*, two spiral steamways *f* and *f'*, the oil-pipe *h*, enclosed within another pipe *g*, the head *b*, the internally and externally threaded nut or head *i*, which fits tightly into the head *b* and supports and regulates the relative position of the pipes *g* and *h*, an oil-supply pipe *n*, suitably connected with the oil-pipe *h*, and a steam-dome *J*, all substantially as specified and set forth.

In testimony that I claim the foregoing as my own I affix my signature in presence of two witnesses.

JNO. F. COATES.
